CONTAINER

Edwin L. Mott, St. Louis, Mo.

Application March 20, 1941, Serial No. 384,251

2 Claims. (Cl. 206—56)

This invention relates generally to containers and, more particularly, to a certain new and useful improvement in containers of collapsible type.

My invention has for its primary object the provision of a collapsible container uniquely constructed for use especially, though not exclusively, with, and during the consumption of, a frozen confection.

My invention has for a further object the provision of a container of the type and for the purpose stated which may be constructed inexpensively and conveniently from a single unitary blank, which is sturdy in construction and neat in appearance, which is initially flat for compact storage when empty and may be readily converted into a substantially flat-bottomed tubular shell of rectilinear shape for accommodating a quantity of frozen confection in the manner of an ice cream bar, which, when appropriately filled with the confection, may be progressively reduced in sections or "peeled off," as it may be said, for exposing for consumption a portion of the confection while the remaining portion of the shell serves as a protective covering and holder for the confection, and which is highly efficient in the performance of its stated functions.

And with the above and other objects in view, my invention resides in the novel features of form, construction, arrangement, and combination of parts presently described and pointed out in the claims.

In the accompanying drawing,

Figure 1 is a plan view of a blank scored for bending and folding for the production of a container of my present invention;

Figure 2 is an elevational view of the finished container in flat or unopened condition;

Figure 3 is a transverse sectional view of the container taken approximately along the line 3—3, Figure 2;

Figure 4 is a perspective view of the container in opened condition ready to receive its contents;

Figure 5 is a top plan view of the opened container; and

Figure 6 illustrates in perspective the container in association with a frozen confection, with part of the container removed or torn away for edibly presenting the confection.

Referring now more in detail and by reference characters to the drawing, which illustrates a preferred embodiment of my invention, the carton is constructed from a blank A die-cut or otherwise formed from a single piece of suitable

container-stock, such, for instance, as heavy cardboard or the like. As shown, the blank A is of any suitable or selected length and is divided substantially midway its length by a transverse score or hinge-line 3 to integrally include relatively foldable main and supplemental sections 1, 2, respectively, approximately of equal length, but with the latter reduced in width relatively to the former.

10 The section 2 is of suitably elongated oblong-rectangular contour with parallel side or longitudinal margins 4 and an end margin 5 parallel with the hinge-line 3, the section 2 being provided longitudinally with score or folding lines 15 6 spaced equidistantly from, and extending from line 3 to margin 5 parallel to, the side margins 4. The fold-lines 6 thus divide the section 2 longitudinally into a so-called front wall forming panel a and side wall forming portions b, b, 20 and at a distance, longitudinally of the blank A, from the hinge-line 3 approximately equal to the distance between each of the fold-lines 6 and the adjacent side margins 4, the central or front wall forming panel a of section 2 is 25 transversely scored for bending, as at 7, for defining a panel, as at c, for partially forming the bottom wall of the container. In addition, the section 2 is also suitably scored for bending along lines 8 extending obliquely from the outer ends of the hinge-line 3 to the points of intersection between the fold-lines 6 and 7.

It will be noted in this connection that the oblique fold-lines 8 are disposed approximately at angles of 45° to the fold-lines 6, and intermediate the fold-line 7 and its free end margin 5, the section 2 is provided transversely from one side margin 4 to the other with zones or lines of weakness, as at 9, 10, suitably spaced at non-uniform distances respectively from the margin 5 and from each other so as to divided the section 2 longitudinally into a plurality of, in the present instance three, sections of unequal length.

The main section 1 is of the same length as, and is substantially wider than, the supplemental section 2 and is formed or provided with a pair of spaced parallel lengthwise extending fold-lines 11, which register or align with the side margins 4 of the section 2, as best seen in Figure 1, and which, as presently appears, define center-lines of 50 the opposite side walls of the finished carton.

Similarly, the section 1 is also formed or provided longitudinally with fold-lines 12, which register with the fold-lines 6 and divide the section 1 longitudinally into a so-called rear wall forming panel d and side wall forming portions e,

e', and likewise at a point spaced, longitudinally of blank A, from the hinge-line 3 a distance approximately equal to the width of the panel *c*, the blank A is transversely scored for bending, as at 13, and for defining a panel *c'* co-operable with the panel *c* in forming the bottom wall of the container, the fold-line 13 being at its opposite ends to the opposite ends of the hinge-line 3 by oblique fold-line 14 similarly disposed approximately at 45° to the fold-lines 12.

The side wall forming portions *e*, *e'*, of the section 1 are obliquely cut off at their inner or lower end, as at 17, at an angle of 45° to the fold-lines 11, the margins 17 aligning with the fold-lines 8 and consequently extending at an angle of 90° to the lines 14. For purposes presently appearing, the portion *e'* is slightly wider, as at 16, over a substantial portion of its length and is obliquely cut inwardly, as at 18, to provide a short section, as at 19, of the same width as the opposite portion *e*.

In addition, the main section 1 is provided with a plurality of transversely extending lines of perforations or zones of weakness; as at 9', 10', which are respectively spaced from the hinge-line 3 by the same distances as the corresponding zones of weakness 9, 10, of the section 2 for coincidence therewith in the finished carton or container, as will presently fully appear.

The blank A, being so scored or marked for folding or bending, is now first folded upon itself about the hinge-line 3, and the sections 1, 2, thereby brought into flatwise overlying registration. Thereupon, the outer marginal portions 15, 15', of the side wall forming members *e*, *e'*, that is to say, the portions thereof intermediate the side margins of the section 1 and the fold-lines 11, are folded over on the lines 11 into facewise overlying relation upon the outer face of, and are for the most part adhesively secured to, the marginal portions *b*, *b*, of the section 2 in the formation of a complete container B, all as best seen in Figures 2 and 3.

In the container B, so formed, it will be noted that the side wall portion *e* will register both along its oblique-inner-end margin 17 and longitudinal margin with the underlying fold-line 6 and the oblique fold-line 8 of the section 2, the portion *e* being adhesively secured preferably throughout such entire area of contact to the section 2.

The other side wall portion *e'* of the main section 1, while also overlying and adhesively fixed to the opposite marginal portion *b* of the section 2, freely projects throughout its marginal extension 16 beyond the fold-line 6 and thereby presents in the finished carton B a narrow free strip providing a pull-off extension or tab, as at 20.

In its thus flat or unopened condition, the carton B may be compactly packed for shipment and handling. In use and for filling, however, the container B may be readily and conveniently opened by pressing the flat carton B inwardly upon the opposite longitudinal margins, that is to say, fold-lines 11 and upwardly upon the hinge-line 3, the flat container B being thereby converted into a flat-bottomed open-topped elongated substantially oblong-rectangular tubular shell having a pair of triangular tabs 21 depending from and being substantially continuations of the side walls *e*, *e'*, and an outwardly projecting tear-off or pull-tab 20, all as best seen in Figures 4 and 5.

In such opened condition, the container B may be suitably filled with a preformed ice-cream bar.

as at C, or may be filled with a viscous ice-cream mix, the container and mix then subsequently being frozen to form a unitary frozen confection. In either case, the completed frozen confection,

- 5 when sold to the consumer, may be attractively edibly displayed by grasping the tab section 20 above the upper coinciding lines of perforations or weakness 9, 9', and tearing off and discarding the upper container section, as shown in Figure 6.
- 10 When the thus-exposed portion of ice-cream C or frozen confection has been consumed, the next succeeding section of the carton B may be similarly torn away or "peeled off," as it may be said. During the consumption of the contained 15 confection C, the confection will ordinarily undergo a substantial rise in temperature and will lose some of its initial hardness. For this reason and also by reason of the unique nature of the depending triangular side wall extensions 21, which co-operate with the hinge-line 3, the container 20 may be squeezed together, collapsing the flattened bottom wall and permitting the somewhat softened confection to be squeezed up out of the remaining lower portion of the container, very 25 much in the manner that a paste may be squeezed out of a collapsible tube. It will, of course, be understood that the ice-cream or frozen confection is progressively squeezed upwardly and consumed, until the container has been collapsed 30 substantially to its initial flat condition, so that at all times the frozen confection will be sanitarily housed in at least the residual portion of the container, soiling of the hands of the consumer being thus obviated.
- 35 It should be understood that changes and modifications in the form, construction, arrangement, and combination of the several parts of the container may be made and substituted for those herein shown and described without departing from the nature and principle of my invention.

Having thus described my invention, what I claim and desire to secure by Letters Patent is,

- 45 1. A container constructed of a single substantially oblong-rectangular blank folded upon itself substantially midway its opposite ends to include main and supplemental equal length sections, said sections being transversely scored adjacent to, and parallel with, said fold-line in the provision of co-operable bottom wall forming portions, the supplemental section being provided longitudinally adjacent its opposite side margins with parallel fold-lines and divided thereby into 50 a front wall forming panel and side wall forming portions, and the main section having a greater width than the supplemental section and being provided with fold-lines aligningly registering with the fold-lines of the supplemental section, 55 said fold-lines of the main section dividing the same into side wall forming portions and a rear wall forming panel, said side wall forming portions of the main section being longitudinally divided by fold-lines into lengthwise extending marginal portions each having a transverse width greater than the transverse width corresponding to the side-wall forming portions of said front wall and being partially foldable over and secured to said side wall forming portions of the supplemental section.
- 60 2. A container constructed of a single substantially oblong-rectangular blank folded upon itself substantially midway its opposite ends to include equal length main and supplemental sections, the latter being provided longitudinally adjacent its
- 65
- 70
- 75

opposite side margins with parallel fold-lines and divided thereby into a front wall forming panel and side wall forming portions, and the main section having a greater width than the supplemental section and being provided with fold-lines aligningly registering with the fold-lines of the supplemental section, said fold-lines of the main section dividing the same into side wall forming portions and a rear wall forming panel, said side wall portions being longitudinally divided by fold-lines into lengthwise extending marginal portions each having a transverse width

5 greater than the transverse width corresponding to the side-wall forming portions of said front wall and being partially foldable over and secured to said side wall forming portions of the supplemental section, and said front and rear wall forming panels being provided with transverse and oblique fold-lines in the production of co-operable portions forming a bottom wall which is integral with both the front and rear walls across 10 substantially the entire width of the container.
